(57) **CLAIM**

The ornamental design for an pin for a fingernail or toenail clipper, as shown and described.

DESCRIPTION

FIG. 1 is an exploded perspective view of my pin for a fingernail or toenail clipper showing both the fixed portion and the removable screw portion;

FIG. 2 is an additional, exploded perspective view;

FIG. 3 is an exploded, right side view, the left side view is identical;

FIG. 4 is a right side view thereof with the screw portion inserted;

FIG. 5 is a front view of the fixed portion;

FIG. 6 is a rear view of my pin for a fingernail or toenail clipper with the screw portion inserted;

FIG. 7 is a front view of my pin for a fingernail or toenail clipper with the screw portion inserted;

FIG. 8 is a top view of the fixed portion only, the bottom view thereof is identical;

FIG. 9 is a top view of my pin for a fingernail or toenail clipper with the screw inserted, the bottom view thereof is identical;

FIG. 10 is a cross sectional view of the fixed portion taken along line 10-10 in FIG. 5;

FIG. 11 is a right side view of the screw portion, the left side view is identical; and,

FIG. 12 is a front view of the screw portion, the rear view being identical to FIG. 6.

The screw portion and the fixed portion of the pin for a fingernail or toenail clipper are disclosed separately for convenience of illustration.
